[57] CLAIM

The ornamental design for a tire, substantially as shown and described.

DESCRIPTION

FIG. 1 is a perspective view of a tire showing my new design it being understood that the tread pattern is repeated throughout the circumference of the tire, the opposite side being the same as that shown;

FIG. 2 is an enlarged fragmentary plan view of the tread pattern thereof;

FIG. 3 is an enlarged fragmentary plan view of the inner surface thereof; and,

FIG. 4 is an enlarged fragmentary side elevational view thereof.

FIG. 1

FIG. 2

FIG. 3

FIG. 4
